(57) **CLAIM**

The ornamental design for a cubic power socket, as shown and described.

DESCRIPTION

FIG. 1 shows a perspective view of a cubic power socket; FIG. 2 shows a front view of the cubic power socket of FIG. 1; FIG. 3 shows a back view of the cubic power socket of FIG. 1; FIG. 4 shows a left view of the cubic power socket of FIG. 1; FIG. 5 shows a right view of the cubic power socket of FIG. 1; FIG. 6 shows a top view of the cubic power socket of FIG. 1; and, FIG. 7 shows a bottom view of the cubic power socket of FIG. 1.

The broken lines illustrate environmental structure and form no part of the claimed design.
